The drawing is a perspective view of the chair.
The rear of the backrest is the same as the front thereof.

The design is characterized by the combination of a substantially cubic open-work base portion having four essentially vertical legs joined by horizontal top side rails, and having a unitary seat and back rest cushion arrangement, said cushions being concavely contoured, the seat cushion being substantially coextensive with the top of the cubic base portion and supported in suspended position between the top side rails, all as shown.

I claim:

The ornamental design for a chair, as shown and described.
